US0D1021000S

(12) **United States Design Patent** (10) **Patent No.:** **US D1,021,000 S**
(45) **Date of Patent:** **** Apr. 2, 2024**

(54) **VALVE ASSEMBLY AND BODY FOR SAME**

(71) Applicant: **Watts Regulator Co.**, North Andover, MA (US)

(72) Inventors: **Peter P. Bouchard**, Ayer, MA (US); **Jason Doughty**, Fitchburg, MA (US)

(73) Assignee: **Watts Regulator Co.**, North Andover, MA (US)

(**) Term: **15 Years**

(21) Appl. No.: **29/803,982**

(22) Filed: **Aug. 17, 2021**

(51) **LOC (14) Cl.** **23-01**

(52) **U.S. Cl.**

USPC **D23/233**

(58) **Field of Classification Search**

USPC D23/233, 235–237, 241, 249, 259
CPC . F16K 27/003; F16K 27/0263; F16K 27/0281

See application file for complete search history.

(57) **CLAIM**

The ornamental design for a valve assembly and body for same, as shown and described.

DESCRIPTION

FIG. 1 is a top perspective view of a valve assembly and body for same;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is bottom view thereof.

The broken lines depict portions of the valve assembly and body for same that form no part of the claimed design.

1 Claim, 6 Drawing Sheets
